STARTER DOSAGE CARD

William B. MacLachlan, John A. Aherne, and Richard E. Morgan, Fayetteville, N.Y., assignors to Bristol-Myers Company, New York, N.Y., a corporation of Delaware

Filed Jan. 30, 1968, Ser. No. 10,371

Term of patent 14 years

(Cl. D9—187)

FIG. 2

FIG. 1

FIG. 5

FIG. 4

FIG. 3

FIG. 6

FIG. 7

FIG. 8

FIG. 9

FIG. 1 is a perspective view of a starter dosage card, showing our new design.

FIG. 2 is a front elevational view of the embodiment illustrated in FIG. 1.

FIG. 3 is an end elevational view of the embodiment illustrated in FIG. 1.

FIG. 4 is a side elevational view of the embodiment illustrated in FIG. 1.

FIG. 5 is a rear elevational view of the embodiment illustrated in FIG. 1.

FIG. 6 is a front elevational view of a second embodiment of a starter dosage card.

FIG. 7 is a rear elevational view of the embodiment of FIG. 6.

FIG. 8 is an end elevational view of the embodiment of FIG. 6.

FIG. 9 is a side elevational view of the embodiment of FIG. 6.

The essential features of the design reside in the full line portions. The pills and printing shown in broken lines are for illustrative purposes only.

We claim:

The ornamental design for a starter dosage card, as shown and described.
